ORVILLE U. DESHA, OF FORT COLLINS, COLORADO, ASSIGNOR OF ONE-FIFTH TO THE
DESHA TYPELEX TRUST ESTATE, OF FORT COLLINS, COLORADO

KEY ACTION FOR TYPEWRITERS AND OTHER MACHINES

Application filed January 27, 1928. Serial No. 249,878.

In regard to certain more specific features thereof, my invention relates to improvements in the associated and coacting parts of a key action and mechanism, comprising 5 coacting means alternatively interlocking and disinterlocking the interpositioned parts connecting the type bar and key lever—the coacting incident of operatively interlocking the intermediate mechanism moving the type 10 bar to printing point upon depression of the key lever and an alternative disinterlocking of said means returning the type bar to normal position while the key lever is in depressed position; also including coacting 15 means for restoring said disinterlocked elements to normal operative interlocked position upon release of the key lever, as a contradistinction between previous devices comprising actuating means at all times operative connecting the type bar and key lever to move the type bar to printing point upon depression of the key lever and means actuating 20 said connection to return the type bar to normal position after the printing 25 impact while the key lever is in depressed position, the latter broad object being the subject matter of an application filed by me November 5th, 1923, Serial No. 672,871, upon which Patent 1,643,203 issued Sept. 20, 30 1927. The applicant also endeavors to point out a clear distinction between this and his copending applications Serial No. 55,227 filed September 8, 1925 and Serial Nos. 178,883, 178,084, 178,085, 178,086, 178,087, 178,088 and 35 178,089 filed March 24, 1927.

Among the objects of the present invention the applicant has endeavored: First, to improve the coacting parts between the key lever and type bar which will provide, among 40 other features, a key action which will be efficient in use, rapid, reliable and silent in operation, and which shall have a light touch for operating the type bars, and reduce the liability of the type to collide or "pile" when 45 operated at high speed. Second, To provide a key mechanism of the above character having few parts simple in construction which will be cheap to manufacture, convenient and easy to arrange and assemble 50 compactly, and construct a key mechanism as to be but little likely to get out of order in usual operation. My invention, accordingly, consists in certain combinations of elements, features of construction, and arrangement of parts, that may readily be incorporated in certain typewriting machines with only slight modification of the structural features of said machines as they now exist, exemplified in the construction hereinafter set forth, which will be more readily understood 55 from an inspection of the accompanying two sheets of drawings and the following specification, the scope of the invention being indicated in the appending claims.

My invention is especially applicable to 60 the usual hand operating machine, as distinguished from a motor driven machine, and is shown in the present case embodied in a machine similar to the Royal standard typewriter. It should be understood, however, 65 that the invention is not restricted to use in a machine of this type, but may be employed wherever found available.

The applicant has endeavored to disclose 70 and describe the construction of the mechanism and manner of its operation and its use in language comprehensible to those versed or skilled in the art who would make or use the device, sufficient to satisfy the requisite of this application, without enumerating every obvious object and advantage, or pointing out all the difficulties and troubles 75 which are cured or ameliorated by his improvement over the present state of the art, the following being a brief description of 80 the several views of the drawings: Fig. I is a sectional elevation of a typewriting machine taken longitudinally and about centrally thereof, constructed in accordance with 85 my invention and showing elements of one key action only in normal position, and also showing so much of the usual mechanism of the machine as is necessary to illustrate how my invention may be embodied therein. Fig. II, represents a view of the key action similar 90 to Fig. I, the key lever being shown depressed and responding the type bar. Fig. II^a is a greatly enlarged sectional view of the reversely breaking roller trip coupling, herein-after described. Fig. III is a key mech- 95 100

anism similar to Fig. I, the key lever being shown in a depressed position and the type bar responding to printing position. Fig. IV is also a key mechanism similar to Fig. I, the key lever being shown in a depressed position and the type bar returned to its initial position. In this manner the key lever may be held down to its limit of movement and the type bar will complete its incident of response to effect the printing and move out of engagement with the platen and complete its cycle of movement regardless of whether or not the key lever is released, thus relieving the key lever of work during the impact printing operation.

The following detailed description sets forth the best mode in which the applicant has contemplated applying the invention. It is understood, of course, that for the sake of clearness and to avoid complication of drawings, elements of the complete machine already known to the art, constituting no part of the present invention, and statements of mere obvious facts, are omitted. In the accompanying drawings similar reference characters indicate corresponding parts in the several views, and in order to facilitate observance of a clear distinction between this and co-pending applications, the reference characters also indicate, as far as practical, the corresponding parts in the several views of my copending applications, referred to above. In the embodiment in Fig. I, more in detail, in which one form of type action is shown as applied to a typewriting machine to which it is particularly adapted, 1 indicates the typewriter frame—1^a indicating the front and 1^b the rear. 5 indicates a common platen mounted as usual to travel longitudinally across the rear upper portion of the machine upon a carriage mechanism. As the carriage mechanism forms no part of the present invention, specific disclosure and description thereof is omitted, as its broad function is well known. 6 indicates one of a series of type bars being radially arranged in a curved row about the same center and are movable about their fulcrum pivot rod 9 on a type bar segment 10, Fig. I, from a horizontal or forwardly extending radial position E as the type 7 forms the arc of vibration G and is brought against the front face of platen 5 to a common printing point A, to an upright radial position as shown by radius F. 12 indicates one of a series of key levers carrying at the front end finger key 13, the rear end pivoted at 14 to bar 14^a in the rear of the machine, and is kept normally in its elevated position by the usual spring 15 supported by bar 15^a, at normal rest the key lever bearing against the underside of the buffer bar 30 above the key lever 12. The key lever 12 is formed with an upward curved arm 16 convexed backwardly 16^a and concaved forwardly 16^b the forward concavity thereof provid-

ing an operative plane, forwardly of said arm and above the key lever, for the operation of a trip roller bob 24, hereinafter described. 17 indicates a key lever rest comprising a cushioned bar 17^a adjustable by a screw 17^b 70 carried by a fixed bar 17^c arranged beneath the key lever, limiting the downward movement of the latter. 18 indicates one of a series of rearwardly disposed vibratory levers corresponding in number with the type bars 6 and key levers 12. Forward ends of the vibratory levers 18 are pivoted at 19 supported by a bar 20, Fig. I, extending across the machine near the front of the latter. 21 indicates a forward pull link, rear end thereof 80 operatively connecting the type bar 6 at 6^a and the forward end operatively connecting the vibratory lever 18 at 18^a. 21^a is a fixed stop collar near the center of the forward pull link 21, and 21^b is a spring support fixed 85 near the rear end of said pull link 21. Said stop collar 21^a and support 21^b being preferably integral with said pull link. 22 indicates a depending trip lever operatively connecting the vibratory lever 18 at 25 intermediate the ends of the latter, and extends downwardly, and operates radially in a plane above the key lever. 24 indicates a trip roller bob carried by the lower end of the depending trip lever 22 operating within the forward 95 concave plane provided by the upward curved key lever arm 16, said trip roller bob communicating and operatively interlocking with the roller grip 26 carried by said key lever arm 16. It is necessary that depending 100 trip lever 22 be of such length and of such form as to permit the normal position of the roller grip 26 to operate between the pivotal connection 25 and trip roller bob 24, that said trip roller bob 24 may cross and recross 105 a reversely breaking line J J drawn from pivot 25 diametrically through roller grip 26, thereby permitting the elements of said reversely breaking roller trip coupling to be interlocked, Fig. I, moving the type bar 6 to 110 printing point upon depression of the key lever and said parts trip out of interlocked position, Figs. II, III and IV, while the type bar returns to normal position; the characteristic form of the depending trip lever 115 22 therefore is mixtilineal, the lower part 22^a being preferably convexed forwardly and the upper part being straight. The roller grip 26 is spool-shaped comprising a roller head 26^a and roller head 26^b on either side of the depending trip lever 22, Fig. II^a. One of the roller heads, 26^a, provides a hollow cylinder hub 26^b forming the pivotal axle 26^b operating in a hole provided by the lower end of the depending trip lever 22, and the other roller head 26^b, provides a cylinder pin 26^c tightly shrunk in said hollow cylinder hub 26^b. The structure of the trip roller bob 24 is identical to that of the roller grip 26, Fig. II^a, except that it is preferable 120 125 130

that the trip roller bob 24 be relatively smaller diametrically than the roller grip 26, the difference in diametrical size enables the small trip roller bob 24, to more readily move to the rear of the axle 26^b of the roller grip 26, thereby enabling the latter to more firmly grip the trip roller bob 24 in operative interlocked position, as shown in Fig. I. 27 is a pull wire spring, the forward end thereof supported by the slidable sleeve 28^c, the rear end supported by a fixed support 21^b. This spring is hereinafter described as a return spring. The return spring 27 moves bodily with the actuating parts intermediate- 15 of the type bar and vibratory lever, the tension of said spring being dormant or inoperative allows momentum to accelerate the movement of the type bar to printing point unrestrained by the tension of said spring 20 upon relatively light depression stroke of the key lever, the latter being also relieved of energizing said spring while operating the type bar. 28 is an actuating thrust rod, the rear end thereof is pivoted at 28^a to a slid- 25 able sleeve 28^c—28^d carried by the forward pull link 21, and the forward end of said actuating thrust rod 28 is pivoted at 28^b to the depending trip lever 22 intermediately the ends of the latter. The slidable sleeve is 30 formed with an aperture or space between the two slidable parts 28^c and 28^d exposing a part of said forward pull link between said slid- 35 able parts with an integral connection 28^e connecting the slidable parts 28^c and 28^d be- 40neath the exposed part of said forward pull link. The stop collar 21^a is fixed on said forward pull link between the slidable parts 28^c and 28^d of said sleeve, the slidable parts 28^c and 28^d of said sleeve alternately com- 45 municating with said fixed collar within said aperture.

It is important that perfect operative alignment of the coacting treads of the respective trip roller bob 24 and roller grip 26 be maintained, therefore, 29, Fig. III, indicates a toothed guide extending across the front part of the machine comprising a series of horizontally disposed teeth 29^a corresponding in number with the vertically dis- 50 posed teeth 29^b.

The lower part 22^a of the depending trip lever operates between two of said horizontally disposed teeth, and the key lever 12 operating between the two corresponding vertically disposed teeth. This toothed guide, therefore, at all times effects perfect operative alignment of the coacting treads of the respective trip roller bob 24 and roller grip 26. 30 is a return buffer bar supported 55 within the lower angle of the toothed guide 29 preadjustable by a screw 30^c in a slot 30^d at either end of the toothed guide; said buffer bar being preferably an intricate part of the key lever stop 30^b. The rear face of the buffer bar 30 is provided with a noise absorbing 60

cushion deadening the impact percussion when struck by the front edge of the lower part 22^a of the depending trip lever 22 limiting the forward movement of the latter, the function of the buffer bar hereinafter being 70 more fully described.

The new mechanical structure, combination of parts and operation thereof are the important factors of the invention in providing the desired function of the key action, a 75 further description of the operative principle, therefore, follows:

The key lever 12 is described as having two incidents of operation before completing its operative cycle, namely: the incident of depression and the incident of release. The incident of depression is disclosed by the movement of the key lever 12 from radius B to radius C, and the incident of release is disclosed by the movement of the key lever 12 back from radius C to radius B. The type bar 6 is described as having two incidents of operation, before completing its operative cycle, namely: the incident of response and incident of recoil. The incident of response 80 of the type bar 6 is disclosed by the movement of the type bar from its initial rest radius E to printing point A, at radius F, forming arc G from pivot 9. The incident of recoil of type bar 6 is disclosed by its movement from 85 the printing point A back to normal rest E thereby completing its operative cycle. These incidents of operation are, of course, common in nonreversely breaking type bar actions in so far as the incident of response, 90 E to A, of the type bar 6 occurs simultaneously with the incident of depression, B to C, of the key lever 12, and the incident of recoil, A to E, of the type bar occurs simultaneously with the incident of release, C 95 to B, of the key lever. In other words, the 100 operative cycle of the type bar and that of the key lever are simultaneous in a nonreversely breaking connection, but the broad function inherent to the present key action 105 relative to the correlation of incidents of operation of the key lever with that of the type bar is in providing the operative expedient by which both the incident of response, E to A, of the type bar and the incident of recoil, A to E, occur during the one 110 incident of depression, B to C, of the key lever, the type bar completing its operative cycle while the operative cycle of the key lever is only half complete.

It is desirable that the cycle of movement of certain intermediate actuating elements interpositioned between the key lever and type bar be simultaneous with the type cycle of movement instead of all being simultaneous with the key lever's cycle of movement. In this case it will be observed that the operative cycle of the vibratory lever 18 and that of the forward pull link 21 are simultaneous 125 with the operative cycle of the type bar, and 130

the operative cycle of the depending trip lever 22 and actuating thrust rod 28 including the slidable sleeve 28^a—28^b is simultaneous with the operative cycle of the key lever. The operative expedient of the present key action is accomplished in this case by reversely breaking a roller trip coupling which forms an operative interlocked connection between the key lever 12 and the depending trip lever 22 moving the type bar to printing point upon depression of the key lever, and the alternative reversely breaking incident of disinterlocking said coacting roller trip returning the type bar to normal position while the key lever is in depressed position the detail mechanism of said coacting roller trip later described as disclosed in Fig. II^a. Upon a rapid operation of the key lever, the alternative disengagement of the elements of the reversely breaking roller trip coupling 24 and 26 permits momentum to carry the type bar 6 from its normal position E relatively faster than its corresponding key lever allowing the type bar 6 to complete its incident of response, E to F and return from F to E by the time the key lever completes its incident of depression B to C and stopped by the key lever rest 17. In other words, the recoil impact of the type bar at the type bar rest 11 is substantially simultaneous with the impact of the key lever at 17, the type bar completing its cycle of movement while the key lever's cycle of movement is only half complete. In order to accelerate the rapid response and recoil of the type bar by overcoming gravity, the weight of the intermediate mechanism is utilized to counterbalance the weight of the type bar by prearranging the point of disconnection as near the key lever as possible.

A further description of the key action follows: Dotted line M M, indicates the correlative relationship of the elements of the reversely breaking roller trip coupling during process of operation, namely, dotted line M M, Fig. I, shows where the actuating thrust rod 28 by means of spring 27 holds the depending trip lever 22 normally in operative interlocked position with the key lever arm 16. In normal position the trip roller bob 24, at the lower end of the depending trip lever 22, is interlocked behind a reversely breaking line J J drawn through the upper border pivot 25 of the actuating plane thence downward diametrically through the roller grip 26. At this stage of operation it will be seen that the roller grip 26 carried by the key lever arm 16 is within the backward concavity of the depending trip lever 22. This position operatively interlocks the elements 24 and 26 of said reversely breaking roller trip coupling effecting response of the type bar 6 upon depression of the key lever. Dotted line M M, Fig. II, shows where the actuating thrust rod 28, by means of its sup-

porting sleeve 28^a communicating with the fixed collar 21^a, has diverted the downward movement of the depending trip lever 22 forwardly and has thereby moved the trip roller bob 24 forwardly across and in front of the reversely breaking line J J, the elements of the reversely breaking roller trip coupling assuming this position about the time the type bar 6 responds to about one-half of its incident of response, as shown by E^a in Fig. II, the momentum of the type bar completing the incident of response of the latter to printing point a, as shown in Fig. III. At this stage of operation it will be seen that the roller grip 26 is without the backward concavity of the depending trip lever 22. The action of the coacting lever roller trip elements 24 and 26 from their normal position Fig. I, to the position shown in Fig. II is unitary, i. e. these elements each revolves on its axis in unison as if they formed a link instead of their treads rolling together, their pivotal movement minimizing friction and lessening wear. Dotted line M M, Fig. III, shows where the actuating thrust rod 28 has diverted the downward movement of the depending trip lever 22 forwardly, and the trip roller bob 24 has moved further downwardly and forwardly away from the reversely breaking line J J, the treads of the roller trip mechanism being disengaged or disconnected. Dotted line M M, Fig. IV, shows where the actuating thrust rod 28 has diverted the downward movement of the depending trip lever 22 forwardly and moving the trip roller bob 24 forwardly and upwardly in front of the reversely breaking line J J, permitting the type bar 6 to recoil while the key lever remains in depressed position. In a reversely breaking key action it is desirable that means be provided whereby the key lever may have a relatively short depression stroke for actuating a full response stroke of the type bar to printing point. Inherent to the present reversely breaking key action, the type bar being unrestrained by the absence of a link connection between it and the key lever, momentum carries the type bar 6 to the printing point A with efficacious impression upon a relatively short depression stroke of the key lever as a contradistinction between the rigid or link connection between the key lever and type bar of nonreversely breaking keys. This operative expedient is accomplished in this case by the alternative disengagement of the elements of said reversely breaking roller trip coupling in the following manner: By referring to Figs. I and II, it will be seen that the normal operative position of the treads of the coacting roller trip elements 24 and 26 are communicative and remain in this position until the type bar 6 reaches a point on arc G to about radius E^a upon depression of the key lever, as shown in Fig. II. At this stage of

operation the key lever has reached the limit of its depression stroke, the latter being stopped by the key lever arrestor 17, and the momentum of the type bar continues the movement of the latter to printing point. The type bar 6, of the present invention therefore, may be operated with about one-fourth of an inch to three-eights of an inch stroke of finger key 13 contrasted with the usual five-eights of an inch inherent to a non-reversely breaking key action.

Inherent to the common noiseless key mechanism, the printing operation is formed by pressure in contradistinction to impact; and the time actually used in making impression by pressure is usually relatively longer than that required by the impact of a type with its movement accelerated by momentum. The generic structure of the present key mechanism, therefore, is similar to that which forms the printing operation by impact, however, the applicant endeavors to provide a type action in this case which may coordinate inherent rapidity of operation with inherent silence of impression. In other words, coordinate the inherent qualities of a noiseless key action with the inherent qualities of a rapidity characterized by efficacious impact. This operative expedient is accomplished by the buffer bar 30 arresting the forwardly diverted movement of the depending trip lever 22 and in turn stopping the forward thrust of the actuating thrust rod 28 and the actuating thrust rod 28 stopping the forward movement of the slidable sleeve 28^d which in turn communicates with the forward end of the fixed stop collar 21^a preventing further actuating movement of the forward pull link 21. The actuating movement of the intermediate elements may be limited by the buffer bar 30 set to arrest the forwardly diverted movement of the depending trip lever 22 just before the type 7 strikes the platen at printing point A, the inherent resiliency of the buffer bar 30 thus absorb the momentum of the type bar, permitting the latter to complete its sector of movement with coordinate rapidity and silent impression, disclosing the first function of said buffer bar.

The applicant also endeavors to provide a key action wherein the incident of recoil of the type bar is relatively quicker than the incident of its response in order that the type arc G may be cleared as rapidly as possible when several keys are being manipulated in rapid succession. It will be seen that the energy manifested by the tension strain under which the intermediate mechanism between the type bar and key lever is subjected to when the forwardly diverted movement of the depending trip lever 22 is arrested and the momentum of the type bar 6 absorbed by the buffer bar 30 effects a relatively quicker incident of recoil of the type bar than its

incident of response, disclosing the second function of the buffer bar 30.

However, where there is no connecting means to retard the recoil of the type bar, and its recoil is further accelerated by the second function of the buffer bar 30, described above, the excessive recoil percussion of the type bar with the cushion rest 11 is also inherent to a reversely breaking roller trip coupling. The applicant, therefore, endeavors, in this case, to provide a key action whereby the recoil of the type bar is absorbed by means which substantially neutralizes the recoil percussion of the type bar with the cushion rest 11, in the following manner: By referring to Fig. II, it will be seen that while the key lever 12 remains depressed, the recoil of the type bar relieves the tension strain upon the intermediate parts occasioned by the buffer bar 30 absorbing the momentum of the type bar, permits the depending trip lever 22 to again partially recoil carrying with it the trip roller bob 24 back in treadle contact with the roller grip 26, and retards the depending trip lever 22 at its forwardly divertic position. In turn the actuating thrust rod 28, by means of the slidable sleeve 28^c—28^d retards the forward end of spring 27, and as the type bar 6 continues to recoil, Fig. IV, it in turn continues to pull the link 21 backwardly, and, by means of the fixed spring support 21^b carried by said forward pull link, the recoil of the type bar expands or energizes said spring 27. It is this process of energizing the spring 27 which counterbalances the major part of the recoiling energy of the type bar 6, thereby neutralizing the recoil percussion of the type bar contacting with the cushion rest 11, disclosing the first function of return spring 27.

By referring to Fig. IV, it will be seen that while the key lever is held depressed the co-acting treads of the trip roller bob 24 and the roller grip 26 are disinterlocked yet are in a communicative position and the rear slidable part 28^c of the slidable sleeve is in communication with the step collar 21^a, this position prearranged to also absorb the excessive recoil percussion of the type bar 6 occasioned by its contact with the cushion rest 11.

It is equally important that reliable and rapid means be provided for restoring the elements 24 and 26 of the reversely breaking roller trip coupling to normal operative position upon release of the key lever. This is accomplished by the second function of the return spring 27 in the following manner: It will be noted, in Fig. IV, that the recoil of the type bar 6 to normal position, by means of the forward pull link 21 and fixed support 21^b moving backwardly, has expanded or energized the return spring 27 and the fixed stop collar 21^a carried by the forward pull link 21 has moved backwardly away

from the slidable sleeve 28^a, and upon release of the key lever 12, as shown in Fig. I, the energy of return spring 27 moves the slidable sleeve 28^a backwardly against the fixed collar 21^a and simultaneously the actuating thrust rod 28 pulls the depending trip lever 22 backward and again interlocking the trip roller bob 24 with the roller grip 26 behind the reversely breaking line J J. It will be seen that should the key lever be released before the type bar has recoiled, the return spring 27 would still effect the interlocked position of the elements 24 and 26 of the reversely breaking coupling and no matter how successively rapid the key lever may be operated the return spring 27 restores the alternatively disinterlocked elements to normal operative interlocked position equally as rapid.

Finally it will be seen that the present invention provides a simple and practical type action which will be rapid and efficient in use, accomplishing, among others, all of the objects and advantages above set forth, therefore the operation and method of use of a type action of this character is believed to be perfectly clear from the above description, a reiteration thereof is believed to be unnecessary. As many changes could be made in the above construction and many apparently widely different embodiments of this invention could be made without departing from the scope thereof, it is intended that all matter contained in the above description, or shown in the accompanying drawings, shall be interpreted as illustrative and not in a limiting sense, and variations may be resorted to within the scope of the invention, and portions of the improvement may be used without others.

Having described my invention, what I claim as new and desire to secure by Letters Patent is:

1. In a key action for typewriter and other machines, a type bar, a rearwardly disposed vibratory lever pivotedly supported by a bar extending across the front of the machine, means operatively connecting the type bar and vibratory lever, a depending trip lever actuating said vibratory lever, a key lever, an upward curved arm intermediate the ends of the key lever forming an integral part of the latter and said arm convexed backwardly and concaved forwardly, a reversely breaking roller trip coupling comprising a trip roller bob supported by the depending trip lever, and a roller grip supported by the key lever arm, the forward concavity of said arm providing an operative plane forwardly thereof and above the key lever for the operation of said trip roller bob for operatively interlocking the elements of said roller trip coupling moving the type bar to printing point upon depression of the key lever, means disinterlocking said coupling and simultaneously re-

turning the vibratory lever, type bar and immediate connection to normal operative position while the key lever is held depressed, means restoring said disinterlocked elements to normal operative interlocked position upon release of the key lever. 70

2. In a key action for a typewriting machine, a type bar, a key lever, a rearwardly disposed vibratory lever, the forward ends thereof pivotedly supported by a bar extending across the machine near the front of the latter, the operative cycle of said vibratory lever being simultaneous with the operative cycle of the type bar, means operatively connecting the type bar and vibratory lever comprising a forward pull link, a reversely breaking roller trip coupling operatively interlocking the depending trip lever and key lever moving the type bar to printing point upon depression of the key lever, a slidable sleeve carried by said forward pull link, an actuating thrust rod operatively connecting said sleeve and depending trip lever reversely breaking said roller trip mechanism after printing impact of the type bar for returning the vibratory lever, forward pull link and type bar to normal operative position while the key lever is in depressed position, means restoring said disinterlocked elements to normal operative interlocked position upon release of the key lever. 80

3. In a typewriting machine, a type bar, a key lever providing an integral arm curved upwardly and forwardly, a rearwardly disposed vibratory lever in front of the machine, a trip lever operatively depending from said vibratory lever, a reversely breaking roller trip coupling operatively interlocking the depending trip lever and key lever arm, a forward pull link connecting the type bar and vibratory lever moving the type bar to printing point upon depression of the key lever, an actuating thrust rod supported at its forward end by the depending trip lever intermediately the ends of the latter, a fixed stop collar near the center of the forward pull link, a slidable sleeve carried by said forward pull link reversely breaking said roller trip coupling for returning the vibratory lever, forward pull link and type bar to normal operative position while the key lever is in depressed position, means restoring said disinterlocked elements to normal operative interlocked position upon release of the key lever. 100

4. In a key action, a type bar, a key lever formed with an upward arm, a vibratory lever rearwardly disposed, a forward pull link operatively connecting the type bar and vibratory lever, a depending trip lever actuating said vibratory lever, a reversely breaking roller trip coupling moving the type bar to printing point upon depression of the key lever, a slidable sleeve carried by said forward pull link comprising two slidable parts 110

with an aperture between said slidable parts, an integral sleeve bar connecting the slidable parts of said sleeve, an actuating thrust rod connecting the integral sleeve bar and depending trip lever, a fixed stop collar carried by said forward pull link between the slidable parts of said sleeve, the forward slidable part of said sleeve communicating with said fixed collar within said aperture diverting the downward movement of the depending trip lever forwardly reversely breaking said roller trip coupling after printing impact for returning the type bar to normal position while the key lever is in depressed position, the rear slidable part of said sleeve communicating with said fixed stop collar within said aperture absorbing the excessive recoil percussion of the type bar occasioned by its contact with its normal cushion rest, means restoring said reversely breaking roller trip coupling to normal operative interlocked position upon release of the key lever.

5. In a type key action and mechanism, a key lever formed with an upward arm supporting a roller grip, a rearwardly disposed vibratory lever, means operatively connecting the type bar and vibratory lever, a depending trip lever operatively connected at its upper end to said vibratory lever intermediately the ends of the latter extending downwardly and operating in a plane above the key lever, said depending trip lever being mixtilineal in form, the upper part being straight and the lower part convexed forwardly, the lower end thereof supporting a trip roller bob operatively interlocking with said roller grip moving the type bar to printing point upon depression of the key lever, means diverting the downward movement of said trip lever forwardly reversely breaking said roller trip coupling after printing impact of the type bar for returning the vibratory lever and type bar to normal position while key lever is in depressed position, means restoring said disinterlocked elements to normal operative interlocked position upon release of the key lever.

6. In a key action and mechanism, a type bar, a key lever with an upward angular arm intermediate of its ends, a rearwardly disposed vibratory lever, a forward pull link operatively connecting the type bar and vibratory lever, a depending trip lever operating said vibratory lever, a trip roller bob pivoted to the lower end of the depending trip lever, a roller grip carried by said key lever arm spool shaped with roller heads on either side of the depending trip lever, one of the roller heads providing a hollow cylinder hub forming a pivotal axle operating in a hole at the upper end of the key lever arm and the other roller head providing a cylinder pin tightly shrunk in said cylinder hollow hub, said roller grip operating

within the backward concavity of the depending trip lever, operatively interlocking the elements of said roller trip coupling, moving the vibratory lever downwardly and the forward pull link forwardly thereby moving the type bar to printing point upon depression of the key lever, a slidable sleeve carried by said forward pull link communicating with a fixed collar on said pull link, an actuating thrust rod carried by said sleeve and depending trip lever diverting the downward movement of said depending trip lever forwardly and swinging said trip roller bob forwardly and upwardly said roller grip moving out of the backward concavity of the depending trip lever reversely disinterlocking the elements of said roller trip coupling for returning the vibratory lever, forward pull link and type bar to normal operative position while the key lever is in depressed position, means restoring said disinterlocked elements to normal interlocked position upon release of the key lever.

7. In a key action, a type bar, a key lever, a rearwardly disposed vibratory lever, means operatively connecting the type bar and vibratory lever, a depending trip lever operating the vibratory lever, a trip roller bob carried by the lower end of the depending trip lever spool shaped with roller heads on either side of the depending trip lever, one of the roller heads providing a hollow cylinder hub forming the pivotal axle operating in a hole at the lower end of the depending trip lever and the other roller head providing a cylinder pin tightly shrunk in said hollow cylinder hub, said roller bob operating within the forward concaved plane provided by the upward curved key lever arm, communicating with and operatively interlocking with said roller grip behind a reversely breaking line drawn through the diametrical roller grip constituting a coupling for moving the type bar to printing point upon depression of the key lever, means reversely breaking said roller trip coupling after printing impact of the type bar for returning the type bar to normal position while the key lever is in depressed position, means restoring said disinterlocked elements to normal operative interlocked position upon release of the key lever.

8. In a type key action, a key lever having an upward curved arm, a key lever rest under said key lever, a type bar, a vibratory lever, means operatively connecting the vibratory lever and key lever comprising a depending trip lever actuating said vibratory lever, a reversely breaking roller trip coupling comprising a relatively large roller grip carried by the key lever arm and a relatively small trip roller bob carried by the depending trip lever with their treads communicatively interlocked, the difference in diametrical size of said coating elements enabling them to more firmly engage in operative interlocked posi-

tion for moving the type bar to printing point upon depression of the key lever, means diverting the movement of said depending trip lever forwardly, disinterlocking the coacting treads of the roller trip coupling, permitting the momentum of the type bar to carry the latter to printing point with a relatively short depression stroke of the key lever limited by a key lever rest means restoring said coacting treads of the elements of the reversely breaking roller trip coupling to normally operative interlocked position upon release of the key lever.

9. In a type key action, a type bar, a key lever, a rearwardly disposed vibratory lever pivoted at its forward end, a forward pull link operatively connecting the type bar and rear end of the vibratory lever, a reversely breaking roller trip coupling operatively interlocking the depending trip lever and key lever arm comprising a roller grip and a trip roller bob operatively interlocked for moving the type bar to the printing point upon depression of the key lever, an actuating thrust rod, a slidable sleeve carried by the forward pull link to which the rear end of the thrust rod is pivoted and the forward end of said actuating thrust rod being pivoted to the depending trip lever intermediately the ends of the latter diverting the downward movement of the depending trip lever forwardly moving said trip roller bob forwardly and upwardly in front of a reversely breaking line drawn diametrically through the said roller grip permitting the type bar to recoil while key lever remains in depressed position, means actuating said slidable sleeve and thrust rod backwardly restoring said depending trip lever and trip roller bob to normal operative position upon release of the key lever.

10. In a typewriting machine, a type bar, a key lever having an upwardly extending arm, a vibratory lever, means operatively connecting the type bar and vibratory lever, a trip lever for actuating the vibratory lever, a reversely breaking roller trip coupling comprising a trip roller bob carried by the depending trip lever and a roller grip carried by the key lever arm operatively interlocked for moving the type bar to printing point upon depression of the key lever, means diverting the downward movement of said depending trip lever and trip roller bob forwardly disinterlocking said roller trip elements, a buffer bar extending across the machine in front of said depending trip lever, a noise absorbing cushion provided by the lower face of said buffer bar communicating with the upper edge of the key lever limiting the upward movement of the latter and deadening the percussion, a resilient noise absorbing cushion provided by the rear face of said buffer bar set to arrest the forwardly diverted movement of the depending trip lever just be-

fore the type bar strikes the printing point, the inherent resiliency of said buffer bar absorbing the momentum of the type bar transmitted through the intermediate mechanism permitting the type bar to complete its sector of movement coordinating inherent rapidity of operation with inherent silence of impression, means reversely breaking said roller trip mechanism after printing impact of the type bar, the second function of said buffer bar effecting a relatively quicker incident of recoil of the type bar than its incident of response for returning the vibratory lever and forward pull link to normal operative position while the key lever is in depressed position, means restoring said disinterlocked elements to normal operative interlocked position upon release of the key lever.

11. In a key action, a type bar, a forward pull link actuating said type bar, a vibratory lever actuating said forward pull link, a depending trip lever actuating said vibratory lever, a key lever with an integral arm upwardly curved, a reversely breaking roller trip coupling comprising a trip roller bob supported by the depending trip lever and a roller grip supported by the key lever arm, the treads thereof operatively interlocked moving the type bar to printing point upon depression of the key lever, means diverting the movement of said depending trip lever forwardly disinterlocking the roller trip treads reversely breaking said coupling after printing impact of the type bar for returning the type bar to normal position while the key lever is in depressed position, a toothed guide extending across the front part of the machine comprising a series of horizontally disposed teeth corresponding in number with a series of vertically disposed teeth, the lower part of the depending trip lever operating between two of said horizontally disposed teeth and the key lever operating between the two corresponding vertically disposed teeth restoring said depending trip lever to its normal operative position effecting operative alignment of the coacting treads of the respective trip roller bob and roller grip upon release of the key lever.

12. In a type key action and mechanism, a type bar, a rearwardly disposed vibratory lever, a forward pull link operatively connecting the type bar and vibratory lever, a depending trip lever actuating said vibratory lever, a trip roller bob actuating said depending trip lever, a key lever providing an upward curved arm intermediately of its ends, a roller grip carried by said arm operatively interlocking said trip roller bob moving the type bar to printing point upon depression of the key lever, means disinterlocking said elements permitting the momentum of the type bar to move the latter to printing point with relatively shorter depression stroke of the key lever, the type bar comple-

ing its cycle of movement to printing point and back to normal position of rest by the action of substantially the first half of the key lever cycle of movement, means restoring the reversely breaking trip roller coupling to normal operative interlocked position of rest by the action of the second half of the key lever cycle of movement.

13. In a key action and mechanism, a type
10 bar held in normal position by a type bar
rest, a rearwardly disposed vibratory lever,
a forward pull link operatively connecting
the type bar and vibratory lever, a depending
trip lever actuating said vibratory lever, a
15 key lever providing a key lever arm, a re-
versely breaking trip link coupling comprising
a trip roller bob supported by the depend-
ing trip lever and a roller grip carried by
the key lever arm moving the type bar to
20 printing point upon depression of the key
lever, a slidable sleeve carried by said for-
ward pull link, an actuating thrust rod oper-
atively connecting the trip lever and slidi-
able sleeve, a fixed spring support carried by
25 the rear portion of said pull link, an actuat-
ing return spring supported by said spring
support and slidable sleeve, said spring mov-
ing bodily forwardly beneath said pull link,
the tension thereof being dormant or ineffec-
30 tive permitting efficacious impact of the type
bar upon relatively light depression stroke of
the key lever, a fixed stop collar carried by
the central portion of said pull link commu-
nicating with the forward slidable part of
35 said sleeve diverting the downward move-
ment of the depending trip lever forwardly
reversely breaking said coupling after print-
ing impact of the type bar, said roller grip
holding the trip roller bob and the depending
40 trip lever in their forwardly diverted pos-
ition and in turn the actuating thrust rod by
means of the slidable sleeve energizing said
spring by the recoil energy of the type bar
neutralizing the recoil percussion of said type
45 bar occasioned by the contact with the type
bar rest, means releasing the energy of said
spring slidings said sleeve backwardly effect-
ing backward movement of said actuating
thrust rod restoring the depending trip lever
50 to normal operative position upon release of
the key lever.

Signed at Fort Collins, in the county of
Larimer and State of Colorado, this 24 day
of Jan., A. D. 1928.
